UNITED STATES PATENT OFFICE.

JEAN RÜD, OF SOLOTHURN, AND CARL KERSCHBAUM, OF ZURICH, SWITZERLAND.

DENTURE.

Application filed July 23, 1923. Serial No. 653,318.

To all whom it may concern:

Be it known that we, JEAN RÜD, a citizen of the Republic of Switzerland, residing at Solothurn, Switzerland, and CARL KERSCHBAUM, a citizen of the Republic of Switzerland, residing at Hinwil, Ct. Zurich, Switzerland, have invented certain new and useful Improvements in Dentures; and we do hereby declare the following to be a clear, full, and exact description of the invention, such as will enable others skilled in the art to which it appertains to make and use the same, reference being had to the accompanying drawings, and to letters or figures 15 of reference marked thereon, which form a part of this specification.

The present invention relates to improvements in dentures and has for its object to provide in an artificial denture or a set of 20 artificial teeth a resilient or elastic packing at the necessary places between the set of teeth and its support, i. e. the roof of the mouth or the jaw respectively. This packing is an improvement over the known suction discs hitherto used for holding dentures 25 in position.

Several constructional examples of the subject matter of the present invention are shown. In the drawing—

30 Fig. 1 shows in section and on an enlarged scale part of the denture, for instance the part of an upper set resting against the palate.

Fig. 2 is a section of a denture similar to 35 that shown in Fig. 1, a different packing strip being, however, provided.

Figs. 3, 4 and 5 are perspective views of dentures provided with a packing according to the present invention.

40 Referring now to the constructional example illustrated in Fig. 1, in the plate body *a* of the set a groove *b* is provided in which an insertion *c* consisting of an elastic material, such as india-rubber, is lodged. The 45 portion of the insertion which is remote of the plate bears snugly against the support *d* (palate or jaw) and forms a packing between the plate and the support which permits air or liquid to pass from left to right 50 when looking at the drawing, but prevents a passage in the opposite direction.

By means of this insertion portions of the denture of any shape can be outlined and packed or tightened. The insertion is preferably formed as a strip. In most cases such a strip will be arranged along the circum-

ference of the denture, as is shown in Fig. 3, whereby it is attained that any displacement of the plate is opposed by the pressure below atmospheric, i. e. the suction action, 60 forming itself inside the tightened space between the plate and its support. Thus the plate or denture itself is the suction surface closely fitting the mucous membrane, and the packing strip surrounds the effective 65 portion of the surface of the plate causing the adhesion of the plate to the mucous membrane. The strip itself is not primarily the means for causing the adhesion, the close fit of the plate does this, the strip merely acts 70 as a packing. This opposing force will be large owing to the comparatively large surface on which the pressure acts. If no outer force tending to cause a displacement is present and if the packing strip fits well to 75 its support the pressure below atmospheric disappears, it is no longer felt by the bearer of the set of artificial teeth and does not give rise to irritations of the mucous membranes.

The recess *b* is arranged on the plate of 80 the set according to requirements, for instance two recesses or grooves may be provided beside each other so that two packing or tightening strips *c*₁, *c*₂ can be arranged to ensure a greater reliability, as is illustrated 85 in Fig. 4, or two or more portions that are independent of each other and enclosed by packing strips can be formed. This arrangement is shown in Fig. 5, in which three such portions *e*, *f* and *g* are enclosed by the 90 packing strips *c*₁, *c*₂ and *c*₃ respectively. It is, however, essential that the extent of the groove corresponds to the requirements in each case and that the tightened zone can be suitably shaped to lie snugly on the palate 95 or the jaw.

In case of the generally used dentures of vulcanized india-rubber or vulcanite the groove can be obtained by inserting previous to the vulcanizing action an easily flexible 100 metal strip *h* in the places where the groove has to be formed. The metal strip *h* (Fig. 2) is of a rectangular cross-section enclosing a T-shaped groove *i*. Into the latter the beaded portion *k* of an india-rubber strip *c* 105 is inserted, whereby the latter is held in position. The outer surface of the metal strip is preferably roughened as indicated in Fig. 2 by dotted lines, to ensure that the strip is firmly embedded in the vulcanite mass. The T-shaped groove of the strip may be filled with a material that can be removed by dip- 110

ping the vulcanized denture on which the strips have been placed in position before the vulcanizing action into a suitable bath. When the material within the groove has 5 thus been removed the rubber strip is inserted into the latter by forcing the beaded portion *h* through the narrow gap *l* of the groove *i*. The metal strip *h* as well as the rubber strip *c* can be made endless to any 10 suitable lengths; or they can be cut off from one piece to the length required; in the latter case care has to be taken that the ends of the strip join well in order to produce tightening zones which are closed all round, further 15 the ends will be arranged at such a place where leakage is not to be expected.

The inserted packing strip *c* can be exchanged.

As the inserted packing strip requires little space and as its application is not limited to a space of a regular shape to be tightened it can be adapted to any requirements and it is well suited therefore for low and partial dentures.

25 We claim:

1. A packing for dentures, comprising a longitudinal flexible strip having a denture engaging bead at one edge and a substantially parallel edge adapted to lie against 30 the mucous membrane.

2. A packing for dentures, comprising a strip of flexible material having a denture engaging bead along one edge and tapering to a thin, substantially parallel opposite 35 edge.

3. A packing for dentures, comprising a flat, flexible, rubber strip having a denture engaging bead at one edge and tapering to a thin, substantially parallel opposite edge.

4. The combination with a denture closely fitting the mucous membrane and having continuous groove surrounding that portion fitting the membrane, a packing strip surrounding such portion and having one edge secured in said groove and the opposite free edge tapered and arranged to engage said membrane.

5. The combination with a denture having a suction surface closely fitting the mucous membrane and a continuous groove surrounding said surface; of a flexible packing strip, having an enlarged edge fitting into said groove and its opposite edge arranged to engage the mucous membrane beyond said surface, and preventing the entrance of air between said surface and membrane.

6. The combination with a denture having a suction surface closely fitting the mucous membrane, a groove completely surrounding said surface, and a metal lining for said groove; of an endless, flexible, soft rubber packing strip having a bead at one edge fitting into said groove and a tapered, substantially parallel, opposite edge to fit against said membrane.

In testimony that we claim the foregoing as our invention, we have signed our names.

JEAN RÜD.

CARL KERSCHBAUM.
